US00D818117S

(12) **United States Design Patent** (10) **Patent No.:** **US D818,117 S**
(45) **Date of Patent:** ** *May 15, 2018

(54) **AIR REMOVAL DEVICE**

- (71) Applicant: **Richard Green**, Santa Monica, CA (US)
- (72) Inventor: **Richard Green**, Santa Monica, CA (US)
- (73) Assignee: **AILNH, LLC**, Boca Raton, FL (US)
- (*) Notice: This patent is subject to a terminal disclaimer.
- (**) Term: **15 Years**
- (21) Appl. No.: **29/596,365**
- (22) Filed: **Mar. 7, 2017**

CLAIM

I claim the ornamental design for an air removal device, as shown and described.

DESCRIPTION

FIG. 1 is a top front perspective view of the claimed design; FIG. 2 is a right side elevation view thereof; FIG. 3 is a left side elevation view thereof; FIG. 4 is a front elevation view thereof; FIG. 5 is a rear elevation view thereof; FIG. 6 is a top plan view thereof; and, FIG. 7 is a bottom plan view thereof.

The broken line showing of air removal device is included for the purpose of illustrating portions of the "article" and forms no part of the claimed design.

The air removal device is shown with symbolic breaks in its length. The appearance of any portion of the article between the break lines forms no part of the claimed design.

1 Claim, 4 Drawing Sheets
